CLAIM

The ornamental design for a luminaire assembly, as shown and described.

DESCRIPTION

FIG. 1 is a perspective front right side view of the luminaire and the fixture of the luminaire assembly;

FIG. 2 is a front view thereof;

FIG. 3 is a right side view thereof;

FIG. 4 is a back view thereof;

FIG. 5 is a top view thereof;

FIG. 6 is a left side view thereof;

FIG. 7 is a bottom view thereof;

FIG. 8 is a perspective front right side view of the luminaire assembly in which the luminaire is clamped in the fixture;

FIG. 9 is a front view thereof;

FIG. 10 is a right side view thereof;

FIG. 11 is a back view thereof;

FIG. 12 is a left side view thereof;

FIG. 13 is a top view thereof;

FIG. 14 is a bottom view thereof;

FIG. 15 is a perspective front right side view of the luminaire assembly in which the luminaire is clamped in the fixture in an alternative position;

FIG. 16 is a perspective front right side view of the luminaire assembly in which the luminaire is clamped in the fixture in a second alternative position;

FIG. 17 is a front view of the luminaire assembly in which the luminaire is clamped in the fixture according to the position shown in FIG. 15;

FIG. 18 is a left side view thereof;

FIG. 19 is a back view thereof;

FIG. 20 is a top view thereof; and,

FIG. 21 is a bottom view thereof.

In an embodiment, the luminaire assembly includes a portable, cylindrical luminaire having four LEDs and a fixture for mounting the luminaire in a vertical or horizontal position. The fixture can be mounted to a seat by screws, by a magnet or by an adherend.
